UNITED STATES PATENT OFFICE.

JOHN H. WILSON, OF CAMDEN, NEW JERSEY.

FIRE-ESCAPE.

SPECIFICATION forming part of Letters Patent No. 325,142, dated August 25, 1885.

Application filed July 7, 1885. (No model.)

To all whom it may concern:

Be it known that I, JOHN H. WILSON, a citizen of the United States, and a resident of Camden, New Jersey, have invented a certain 5 Improved Fire-Escape, of which the following is a specification.

My invention relates to that class of fire-escapes in which a sliding block is combined with a rope, and in which the weight of the 10 body automatically locks the device, to prevent the descent of the person using it until specially adjusted to permit such descent.

In the accompanying drawings, Figure 1 is a perspective view of my improved fire-escape. Fig. 2 is a section on the line 1 2, Fig. 15 2; and Fig. 3 is a section on the line 3 4, Fig. 2.

A is a sliding block, which is provided with a hook or eye, a, for the attachment of a band or other device, M, to support the body of the 20 person using the fire-escape, and through this block passes the rope B, which is intended to be suspended at the upper part of the building and extends down to the ground. This block A is slotted transversely, and is provided with two rods or bars, E and E', the 25 former being fixed, while the rod E' is free to have a movement toward and from the rod E, to which it is adjacent. In the present instance I have shown the rod E' as pivoted at 30 e, Fig. 1, and free to have a movement at the other end, but acted on by the cam-lever F, which is pivoted to the block at f, the cam-lever being of such a character that when its projecting outer end is pressed down by the 35 hand of the operator the bar E' will be pushed away from the bar E, as shown by full lines in Fig. 2.

From the slotted part of the block A to opposite ends thereof extend openings r', through 40 which the rope B is adapted to pass, and this rope on its way through the block passes around and between the two bars E and E'. In the present instance I have shown the rope as first passing down underneath the bar E', 45 then up and over and completely around the bar E, passing between the two bars, and then back again between the two bars and out through the opening r' at the bottom; but the particular manner of arranging the rope is not 50 essential, so long as it passes around and between the two bars.

I prefer to provide each bar with a guide-pin,

p, Fig. 2, so as to separate the coils of rope, and prevent them from lapping over and binding on each other.

55

It will be seen from the above that when the weight of the body is brought upon the block A the strain on the rope will force the lower bar, E', up toward the fixed bar E, and so grip the coils of rope between the two bars, so as to prevent the block A from sliding on the rope, and the body in the support M therefore cannot descend until the cam-lever F is pressed down by the person using the escape, so as to move it from the position shown by dotted 65 lines, Fig. 2, to the position shown by full lines, to separate or move the bar E' away from the bar E, and leave the rope free to slide around the bars, and allow the block A, carrying the person, to descend.

70

It will be understood, of course, that the block A may be suspended by the hook a, or otherwise, and the person or weight to be lowered being secured to the rope B, then by a proper manipulation of the cam-lever F by the 75 person at the point where the block is hung the body or other weight may be allowed to descend.

For the sake of lightness with strength and durability, I form the bars E and E' of 80 cylindrical strips of wood having sheet-metal sheaths s over them, as illustrated in Fig. 3, the sheaths being preferably of brass, and the cam-lever F may also be made of wood, if desired, with a metallic facing, t, as shown in 85 the drawings.

As a matter of convenience, and to bring the parts in close relation to each other, I slot the 90 end of the bar E for the reception of the cam-lever F, as shown in Fig. 1; but this is not essential.

I claim as my invention—

1. The combination of a rope with a block having two bars, E and E', one fixed and the other movable toward and from the fixed bar, 95 the said rope being passed around and between the bars, substantially as set forth.

2. The combination of a rope, a block having a fixed bar, and an adjacent movable bar around and between which the rope passes, with a 100 cam-lever to separate the two bars against the strain of the rope, substantially as described.

3. The combination of a rope, a block having a fixed bar, and an adjacent bar pivoted at one

end to the block, with a cam-lever to separate the two bars against the strain of the rope, which passes around and between the bars, substantially as specified.

- 5 4. A block for a fire-escape, having bars for the passage of the rope, said bars being of wood with sheet-metal sheathing, as set forth.

In testimony whereof I have signed my name to this specification in the presence of two subscribing witnesses.

JOHN H. WILSON.
